BANDCUTTER SHARPENING MACHINE

Joseph Hexter and William E. Lanham, Atlanta, Ga., assignors to Columbia Baking Company, Atlanta, Ga., a corporation of Delaware

Application February 4, 1949, Serial No. 74,524

4 Claims. (Cl. 51—38)

1

This invention relates to a band cutter sharpening machine and more particularly to a machine of the kind specified, which is adapted to automatically index a band cutter past a sharpening station in timed relation to the movement of reciprocating sharpening tools.

It is an object of the invention to provide a band cutter sharpening machine having therein a band cutter course, which is adjustable to the length and pitch of the cutter on which the sharpening operation is being performed.

It is a further object to provide a band cutter sharpening machine having therein a pair of reciprocating sharpening tools which are operative along the course of a band cutter, and which are accurately and readily adjustable with respect to their operating course.

Further important objectives and advantages of the machine will appear from a reading of the following specification in light of the drawings forming a part hereof, in which drawings:

Fig. 1 is a plan view of the band cutter sharpening machine;

Fig. 2 is a side elevational view;

Fig. 3 is a transverse cross-sectional view on line 3—3 of Fig. 1; and

Fig. 4 is a transverse cross-sectional view on line 4—4 of Fig. 1.

The band cutter sharpening machine herein embodies a frame member 10, on which are mounted for rotation a plurality of guide sheaves 12 and 14 arranged in a plane to turn about axes disposed perpendicularly to the plane of the sheaves. The sheaves 12 and 14, together with other guiding devices to be referred to herein-after, constitute a cutter guide course for supporting a band cutter 16. Operating mechanism is associated with one of the sheaves, herein specifically the sheave 14, for imparting periodic indexing movement thereto for the purpose of advancing the band cutter 16 past a pair of grinding wheels 18 and 20. The grinding wheels 18 and 20 are positioned along the cutter guide course for contact with a band cutter thereon. Means for imparting timed reciprocating movement to the grinding wheels 18 and 20 has been provided, as shall be described hereinbelow.

More specifically, the band cutter course includes, in addition to the main sheaves 12 and 14, a plurality of idle sheaves 22, 24, 26 and 28, about which the band cutter 16 is trained, the idle sheaves 24 and 26 being located, respectively, at the cutter grinding zones in which the grinding wheels 18 and 20 have their effective operation.

The grinding course defining sheaves are jour-

2

naled for rotation in suitable bearings carried by the machine frame 10. The indexing sheave 14 is rotated periodically in step-by-step movement for the purpose of advancing the band cutter 16 the distance of a tooth at each step. The mechanism for imparting the step-by-step rotation to the indexing sheave 14 will now be described.

Mounted in the machine frame 10 is a geared motor 30 having a shaft 32 extending therefrom, the shaft 32 being disposed in a direction parallel to the longitudinal center line of the machine. Fixed to the shaft 32 is a chain sprocket 34, about which is trained a sprocket chain 36. Disposed in substantially parallel relation to the motor shaft 32 is a shaft 38, to which is fixed a chain sprocket 40 driven by the sprocket chain 36, the chain being trained about an idle sprocket 37. The hub of the sprocket 40 has formed in one face thereof a series of clutch teeth 42 which engage with corresponding clutch teeth on a sliding clutch member 44, which is splined to the shaft 38. When an operating member 46 is moved laterally, it effectively moves the clutching collar 44 into clutching engagement with the teeth 42 on the sprocket 40, thereby conditioning the shaft 38 for rotation under the influence of the sprocket chain 36.

Fixed for rotation with the shaft 38 is a rotary cam 48 which lies in contact with a cam follower on an indexing lever 50, the indexing lever being mounted for swinging movement at its lower end on a bracket 52 which extends laterally from the frame of the machine. The upper end of the indexing lever 50 has an operative connection with an index plate rod 54, the connection herein being shown as a slot and pin connection. The lever 50 has a laterally projecting pin 56 which extends into a slot 58 at the end of the indexing plate rod 54. An adjusting screw 60 is provided at the end of the indexing plate rod 54 for the purpose of determining the position of the pin 56 in the slot 58.

One end of the frame 10 carries a bracket 62 in which is journaled for rotation a shaft 64, the shaft being vertically adjustable by manipulation of a bearing screw 66. The bearing screw 66 is carried by a supporting bracket 68 which extends under the lower end of the shaft 64. Mounted on the shaft 64 for free rotation with respect thereto is an indexing gear 70 and underlying the gear 70 for rotation with respect to the shaft 64 is an indexing plate 72. One end of the indexing plate extends beyond the periphery of the indexing gear 70 and in the extending end

thereof is a pivot pin 73 which receives and rotatably secures the inner end of the indexing plate rod 54. Swingably mounted on the pin 73 is a spring biased ratchet tooth 74. The mechanism described is effective to transmit motion from the indexing lever 50, through the index plate rod 54, to the indexing plate 72, the pawl 74, and the indexing gear 70. In one direction of movement the pawl 74 carried on the extending end of the indexing plate 72 will engage the teeth of the indexing gear 70 and advance such gear through the distance of a single tooth.

In order that the indexing plate 72 may be swung in the opposite direction without the pawl 74 having a rotative effect on the indexing gear 70, a detent mechanism operative on the teeth of the indexing gear 70 has been provided. Accordingly, there is affixed to the frame a detent housing 76, in which is mounted a detent 78 for sliding movement against the tension of a spring 80. The spring 80 at its outer end bears against the end wall of the housing 76 and at its inner end it bears against a shoulder 82 formed on the detent. The inner end of the detent is in radial alignment with the teeth of the indexing gear 70 and its free inner end is so shaped as to lie between adjacent teeth of the gear for holding the gear against rotative movement when the detent and the teeth are in engagement. The outer end of the detent has formed thereon a head. With the head is engaged the upper free end of a detent operating bar 84, the lower end thereof being pivoted in the bracket 52. The shaft 38 carries a cam 86 which lies in contact with a cam follower on the detent operating bar 84. As a consequence, the rotation of the shaft 38 will also be effective through the cam 86, the detent operating bar 84 and the detent 78 to release the indexing gear 70 for rotation. The shape and position of the cams 48 and 86 are such as to relate the movement of the indexing device and the detent device, respectively, this relation being such that when the detent 78 is withdrawn from contact with the indexing gear 70, the indexing plate 72 through its connecting instrumentalities will rotate the indexing gear 70 through the distance of a single tooth. At the end of the gear rotation the detent cam again permits projection of the detent 78 into gear holding position under the influence of the spring 80. Springs 79 and 81 retain the levers 50 and 84 in constant contact with their respective operating cams.

Rotative motion is transmitted from the indexing gear 70 to the indexing sheave 14 through an adjustable connection, which includes a stud 88 rotatably carried by the upper face of the indexing gear 70 and extending therefrom to a point above the indexing sheave 14. The stud 88 is suitably threaded for the reception of an adjusting screw 90. The adjusting screw 90 threadedly engages a stud 92 extending upwardly from the upper face of the indexing sheave 14. The stud 92 is rotatably mounted in a spoke of the indexing sheave 14 so that the position of its screw threaded passage may be maintained in alignment with the adjusting screw 90 throughout any given range of adjustment.

The sheave 12, which constitutes one of the main elements of the band cutter course, is journaled for rotation in a block 94. The block 94 is slidably mounted in a guideway bracket 96 extending outwardly from an end of the frame 10, the same being positioned at substantially the center line of the frame structure. The slid-

ing block 94 may be longitudinally adjusted by rotation of an adjusting wheel 98, thereby increasing or decreasing the length of the band cutter course and consequently accommodating the machine to band cutters of various lengths.

The frame 10 includes a plurality of transverse bed members 100 on the upper face of which is carried a pair of longitudinal rails 102. The rails 102 are adapted to carry a grinding tool carriage structure 104. The carriage structure consists of a plurality of longitudinal rails 106 which are supported on transverse tie rods 108. The tie rods 108 project laterally beyond each side of the carriage structure to constitute axles which rotatably mount flanged wheels 110 for supporting the carriage structure on the bed rails 102. Supported on the longitudinal rails of the carriage structure are a pair of oppositely disposed motor mountings 112, each of which constitutes a frame designed to slidably receive a motor mounting plate 114. To the plate 114 is pivoted one end of a motor base 116, the pivot structure on each mounting plate being at the outer end thereof and consisting of a pair of ears 118 extending upwardly from the plate and receiving between them on a pivot pin the reduced throat of the motor base 116. The opposite end of the motor base is supported by an adjusting screw 120. It follows, therefore, that the motor mounting plate 114 may be readily adjusted in a lateral direction by manipulating an adjusting screw 122, and the motor base 116 may be tilted towards or away from the band cutter course by adjusting the screws 120 at the free end thereof.

Attached to each motor base 116 are grinding tool driving motors 124 and 126, having fixed to their shafts the before mentioned grinding wheels 18 and 20, respectively.

As hereinbefore noted, the grinding tool carriage 104 is adapted to be reciprocated in timed relation to the indexing movement of the indexing sheave 14. Accordingly, mechanism has been provided for reciprocating the grinding tool carriage including the grinding wheels 18 and 20 past the grinding zones of the band cutter course after each indexing movement of the indexing sheave 14. Specifically, the mechanism consists in a driving sprocket 128 fixed for rotation to the motor shaft 32. The sprocket 128 is adapted to drive a sprocket chain 130 which is in engagement with a free running drive sprocket 132 mounted for rotation on a longitudinally disposed shaft 134. The hub of the sprocket 132 has formed therein a clutch face 136 adapted to engage with a confronting face of a shaft carried clutch mechanism 136. The confronting clutch faces may be placed into operative position through manipulation of a clutch operating lever 138. When the confronting faces of the sprocket 132 and the clutch device 136 are in engagement, the parts are conditioned to permit the sprocket chain 130 to impart rotational movement to the longitudinal shaft 134. At one end of the shaft 134 is keyed a beveled gear 140, which in turn constantly meshes with a beveled gear 142 carried at one end of a transverse shaft 144. The opposite end of the transverse shaft 144 has fixed thereto a sprocket 148, which engages a sprocket chain 148. The sprocket chain 148 in turn engages a sprocket 150 attached to one end of the transverse carriage drive shaft 152. To the opposite end of the carriage drive shaft 152 is attached a crank plate 154. Eccentrically connected to the crank plate 154 is one end of a pitman 156, the other

end of the pitman having an operative connection with an oscillating shaft 158. The ends of the oscillating shaft 158 are journaled in bearings on the side rails 106 of the carriage structure 104.

In use of the machine a band cutter is trained over the indexing sheave 14, about the idle sheaves 22, 24, 26 and 28, and about the sheave 12. The blade is then put under the desired tension by manipulating the adjusting wheel 98, which moves the axis of the idle sheave 12 in a longitudinal direction. A gauge or pointer 160 is provided for the purpose of assisting in positioning the blade for the desired pitch and scallop, and to indicate whether the hollow ground scallop of the blade will meet the face of the grinding stones 18 and 20 on the right radius.

Should it be necessary to adjust the plane of the blade in the grinding course and particularly for the purpose of adjusting the pitch of the scallop, no matter how slight, to compensate for elongation of the blade due to use or repeated regrinding, it is necessary merely to adjust the screw 66 which bears on the end of the indexing sheave shaft 64 and thereby raise or lower the shaft and the indexing sheave 14. This operation is effective for the reason that the peripheral rim of the sheave against which the cutter rests is slightly tapered from bottom to top, and consequently, a slight adjustment with respect to the plane of the course will result in the necessary arrangement of the cutter in relation to the grinding tools at the grinding zones.

After the cutter has been positioned and adjusted in its course the machine is conditioned for a continuous grinding operation with respect to the cutter, and such operation may proceed unless for some reason the grinding wheels 18 and 20 require adjustment with respect to the grinding zone of the course. Should an adjustment be necessary, the grinding wheels may be laterally adjusted towards and away from the sides of the cutter by turning the adjusting screws 122. Furthermore, should the elevation of the grinding wheels require adjustment, such adjustment may be achieved by turning the screws 120 and thereby pivoting the motor base 116 in the supporting ears 118.

Assuming all adjustments to have been made, it remains only to energize the motors 30, 124 and 126 to set the machine in operation. Once the grinding operation has been started under properly adjusted conditions, the machine operation thereafter is continuous and automatic. As herein described, operation of the motor 30 will effectively drive the shaft 28 when the clutch 44 has been moved into contact with the clutch teeth 42 on the drive pinion. The cams 48 and 86 rotate in unison with the shaft 38, and consequently, the indexing and detent mechanisms are operative without further attention. The cam 86 will operate to withdraw the detent 78 from contact with the teeth on the indexing gear 10 and as soon as the gear has been released, the cam 48 will be in such position as to reciprocate the indexing plate 72 through one position. Upon rotation of the indexing gear 10 and consequently the indexing sheave 14 through one position, the detent 78 will again become operative to hold the indexing mechanism against further movement while the grinding tools are operating on that portion of the cutter presented at the grinding zones.

The grinding cutters are reciprocated in timed relation with the indexing of the cutter through

the cutter course and this, briefly, is accomplished through the drive shafts 134 and 144, the sprocket chain 146 and the shaft 152. It has heretofore been pointed out that the pitman 156 interconnecting the crank plate 154 and the carriage shaft 158 effectively reciprocates the grinding tool carriage along the tracks 102 constantly while power is applied to rotate the shaft 134. The relation of the carriage movement and the indexing mechanism is such that the indexing device operates twice for each revolution of the crank plate 154. Since these parts operate in unison and in timed relation, it will appear that each section of the cutter passing through the grinding stations is subjected to the same degree of treatment by the grinding wheels 18 and 20, and that the proper grinding of a complete band cutter is entirely automatic once the operation has been initiated. It follows also that since each section of the cutter is subjected to the same degree of grinding, a uniform grinding follows, with the result that the cutter is equally sharp and well ground throughout its entire length.

The invention has been illustrated with respect to a single form in which it is presently embodied in operative form, but this form has been used for the purpose of illustration only. Changes and modifications may be made in the machine without departing from the spirit of the claims that follow.

We claim:

1. In a band cutter sharpening machine, a plurality of guide sheaves arranged in a plane to turn about axes disposed perpendicular to the plane of the sheaves constituting a cutter guide course for supporting a band cutter, means associated with one of said sheaves for imparting periodic indexing movement thereto, means for adjusting one of said sheaves in a radial direction within the plane of the course for adjusting the length of said course to accommodate the same to band cutters of different lengths, a driven grinding wheel disposed at each side of said course, and common means for imparting a straight line reciprocating movement to said grinding wheels.

2. In a band cutter sharpening machine, a plurality of guide sheaves arranged in a plane to turn about axes disposed perpendicular to the plane of the sheaves constituting a cutter guide course for supporting a band cutter, means for adjusting one of said sheaves in said course in an axial direction, means associated with one of said sheaves for imparting periodic indexing movement thereto, a driven grinding wheel disposed at each side of said course, and common means for imparting a straight line reciprocating movement to said grinding wheels.

3. In a band cutter sharpening machine, a plurality of guiding sheaves arranged in a plane to turn about axes disposed perpendicular to the plane of the sheaves constituting a cutter guide course for supporting a band cutter, means associated with one of said sheaves for imparting periodic indexing movement thereto, a pair of grinding wheels mounted on a common carriage, means for supporting and guiding said carriage in a straight line along a part of said cutter guide course, said wheels being disposed at opposite sides of said course, and common means for imparting a reciprocating movement to said carriage.

4. In a band cutter sharpening machine, a plurality of guide sheaves arranged in a plane

to turn about axes disposed perpendicular to the plane of the sheaves constituting a cutter guide course for supporting a band cutter, one of said sheaves being mounted for periodic indexing movement, driven grinding wheels disposed at opposite sides of said course, a common carriage for supporting said wheels, means supporting said carriage for straight line movement along said cutter course means for adjusting said wheels in a radial direction on said carriage, means for tilting said wheels on said carriage, and common means for reciprocating said carriage along said cutter course and for imparting periodic indexing movement to said sheave.
